CLAIM

The ornamental design for a packaging for facial wipes, as shown and described.

DESCRIPTION

FIG. 1 is a perspective view of a packaging for facial wipes; FIG. 2 is a top view of the packaging of FIG. 1; FIG. 3 is a bottom view of the packaging of FIG. 1; FIG. 4 is a side elevation view of the packaging of FIG. 1; FIG. 5 is a second side elevation view of the packaging of FIG. 1; FIG. 6 is a third side elevation view of the packaging of FIG. 1; FIG. 7 is a fourth side elevation view of the packaging of FIG. 1; FIG. 8 is a top view of the packaging of FIG. 1 in an unsealed configuration. FIG. 9 is a perspective view of another embodiment of a packaging for facial wipes; FIG. 10 is a top view of the packaging of FIG. 9; FIG. 11 is a bottom view of the packaging of FIG. 9; FIG. 12 is a side elevation view of the packaging of FIG. 9; FIG. 13 is a second side elevation view of the packaging of FIG. 9; FIG. 14 is a third side elevation view of the packaging of FIG. 9; FIG. 15 is a fourth side elevation view of the packaging of FIG. 9; and, FIG. 16 is a top view of the packaging of FIG. 9 in an unsealed configuration. The broken lines are included for the purpose of illustrating unclaimed portions of the packaging for facial wipes and form no part of the claimed design.
